UNITED STATES PATENT OFFICE.

GEOORGES THÉODORE VALLÉE, OF PARIS, FRANCE.

BUFFER FOR USE WITH WOOD PAVING.

1,028,802.

Specification of Letters Patent.

Patented June 4, 1912.

Application filed May 13, 1910. Serial No. 561,117.

To all whom it may concern:

Be it known that I, GEORGES THÉODORE VALLÉE, a citizen of the Republic of France, and a resident of 5 Rue St. Ambroise, in the city of Paris, Republic of France, engineer, have invented a Buffer for Use with Wood Paving, of which the following is a full, clear, and exact description.

It is well known that the wood paving of roadways exerts a considerable pressure on the curbs of footpaths, both by reason of the swelling of the wood, under the action of humidity, and of the settling produced by the passage of heavy vehicles. This pressure drives back, toward the interior of the footpaths, the stone curbs, so that the layer of bitumen or other surface on the footpath is displaced, which involves frequent repairs. Besides, the swelling of wood paving produces also undulations longitudinally to the roadways which are the cause of frequent repairs. The above disadvantages of wood paving are also seen on tramway tracks, by their modifying the normal spacing of the two rails, bending the curves as well as the junctions and switches.

The present arrangement remedies the above disadvantages, by taking up the thrusts which may be produced. This arrangement consists in a kind of buffer rigid in one direction and flexible in the other, so as to resist the rolling of vehicles and to yield to the thrusts of the wood paving, by placing it along the footpaths, across the roadway, against the tramway rails, in the middle of the tracks and across the same.

The invention will be described by way of example in the accompanying drawings in which:

Fig. 1 shows in cross section the present arrangement applied between the curb of a footpath and the first longitudinal row of wooden paving blocks of the roadway. Fig. 2 shows in plan view a wood paved roadway protected in the transverse and longitudinal direction by buffers. Fig. 3 shows in side elevation a detached buffer. Fig. 4 is a plan view of the buffer shown in Fig. 3. Fig. 5 is an end view of the buffer illustrated in Figs. 3 and 4. Fig. 6 illustrates in cross section a roadway with tramway tracks protected by buffers. Fig. 7 is a plan view corresponding to Fig. 6. Fig. 8 shows in cross section and in use a modified form of buffer.

As shown in the drawing (Fig. 5) the

buffers entering in this arrangement, are constituted by two sheet-iron shells a and a' fitting in one another so that the two heads a^2 a^3 are diametrically opposite to each other. These buffers thus formed and placed edgewise, that is to say with the cheeks a^4 a^5 in a vertical plane, have the advantage of offering a great resistance to the crushing stress, under the weight of vehicles. Moreover, the heads a^2 a^3 of the shells are dished and this still contributes to give the cheeks of the shells a certain rigidity in the vertical plane, while permitting these cheeks to come nearer together in the transverse direction, by yielding to the thrust or pressure of the wood paving, so as to take up as it were the effects resulting from this pressure. Each of these buffers A of a general prismatic quadrangular shape (Figs. 3, 4 and 5) constitutes an element and several elements are connected between them by means of an inner covering plate or collar b introduced at one end between the two shells and then riveted and inserted at the other end between the two shells of the following element. The elements A thus constituted are placed between the curbs c of the footpaths and the first longitudinal row of wooden paving blocks d , as illustrated in Figs. 1 and 2 of the drawings. The same elements may also be placed on one or more lines parallel to the axis of the roadway and transversely thereto so as to divide the paving into squares. Thus the small channels or slots which must generally be made in the said pavings are avoided. In the longitudinal direction of the roadway, the elements A may be of a relatively great length, while their length is much smaller in the transverse direction so that they may easily conform themselves, as the ordinary paving blocks, to the curve of the roadway. In the latter case, the buffers may be beveled, especially when they are to be applied on curves of small radius. When the elements are to be placed along footpaths, one of their cheeks is vertical on the side of the roadway and the other cheek is inclined toward the curb of the footpath, so as to conform itself to the inclination of this curb, as indicated in the drawings, Fig. 1. All these elements may rest on a layer of concrete or of cement and may be applied to any kind of roadways, quays or any other wood paved surface.

In order to prevent the deteriorations produced by the pressure of wood paving on tramway tracks, buffers A may be placed near the rails e or between the rails and parallel thereto, as illustrated in Figs. 6 and 7. Buffers may also be placed in the intermediate space between the tracks and in the longitudinal direction, as shown by the same figures. Other buffers may also be arranged transversely to the track and to the intermediate space between the tracks.

Instead of using buffers constituted by two shells fitting into one another, as above described, I may use buffers A¹ A², formed by two chased parts fitting in one another and riveted as shown in Fig. 8. These buffers are applied against the web of the rails e.

The forms, details, accessories, materials and dimensions of the above devices may of course vary without changing the principle of the invention.

Claims:

1. A buffer of the character specified, comprising two shells oppositely arranged and fitting one within the other, the cheeks of these shells fitted one within the other being thus doubled. 25

2. A buffer of the character specified, comprising two shells oppositely arranged and fitting one within the other, the cheeks of these shells fitted one within the other being thus doubled, the body portion of one of the shells having the shape of the tread under surface of a rail. 30

35 The foregoing specification of my arrangement for preventing the deterioration of the footpaths and tramway tracks by the pressure of the wood paving of roadways, signed by me this third day of May 1910.

GEORGES THÉODORE VALLÉE.
